(57) CLAIM

The ornamental design for a cosmetics container, as shown and described.

DESCRIPTION

FIG. 1 is an exploded perspective view of a cosmetics container with the container lid removed from the container base.

FIG. 2 is an additional, exploded perspective view of the cosmetic container of FIG. 1.

FIG. 3 is a top perspective view of the cosmetics container of FIG. 1 with the container lid in place over the container base.

FIG. 4 is a bottom perspective view of the cosmetics container of FIG. 3.

FIG. 5 is a front view of the cosmetics container of FIG. 3.

FIG. 6 is a back view of the cosmetics container of FIG. 3.

FIG. 7 is a top view of the cosmetics container of FIG. 3.

FIG. 8 is a first side view of the cosmetics container of FIG. 3.

FIG. 9 is a second, opposite side view of the cosmetics container of FIG. 3; and,

FIG. 10 is a bottom view of the cosmetics container of FIG. 3.

The stippled shading and straight line shading illustrate a contrasting appearance. The broken line disclosure of the lipstick in FIGS. 1 and 2 illustrates the environment. The remaining broken lines illustrate portions of the cosmetics container. None of the broken lines form part of the claimed design.
